UNITED STATES PATENT OFFICE.

EDWARD A. WELDS, OF READING, MICHIGAN.

FENCE.

SPECIFICATION forming part of Letters Patent No. 400,377, dated March 26, 1889.

Application filed January 10, 1889. Serial No. 296,005. (No model.)

To all whom it may concern:

Be it known that I, EDWARD A. WELDS, a citizen of the United States, residing at Reading, in the county of Hillsdale and State of Michigan, have invented new and useful Improvements in Fences, of which the following is a specification.

My invention relates to that class of fences wherein the sections are strengthened and 10 braced by wires, and the purpose thereof is to provide means whereby the trussing or supporting tension of such wires may be greatly increased in order to produce a stiff and firm structure.

15 The invention consists in the several novel features of construction and new combinations of parts hereinafter fully set forth, and then definitely pointed out in the claim.

Referring to the accompanying drawings, 20 Figure 1 is a side elevation of a fence embodying my invention. Fig. 2 is a transverse section of the same. Fig. 3 is a detail view.

In the said drawings, the reference-numeral 1 denotes the sills, which rest upon stones or 25 other supports in the ground and are arranged transversely to the fence-sections. Upon each sill is placed a post formed of two parallel sections, 2, which rest on the central portion of the sill. Between said sections 2 are laid the ends of the fence-rails 4, alternating one with another in the adjacent sections and at the ends of the line of fence separated by blocks 5.

Connected to the upper end of each post-section 2 is a wire, 6, which is then carried over the upper rail, 4, and then down to the end of the sill 1, where it is passed through a staple, 7, projecting from the vertical face of the sill and carried thence to a bolt or staple, 8, to which its end is attached.

A similar wire, 9, is connected to the other post-section 2, and crossed above the upper fence-rail, 4, whence it is carried down to the sill and attached in the manner described, the two wires 45 6 and 9 crossing each other above the upper rail and having bends bearing directly upon the top edges of the uppermost rails to press and hold the latter down, and thereby bind all the rails tightly one upon the other, 50 to prevent their vertical movement and provide a firm, rigid, and substantial structure. To produce a high tension upon these wires I

drive wedges 10 between the sill and those portions of the wires lying between the staples 7 and the bolts or staples 8. To firmly secure 55 the staples 7 and the bolts or staples 8 and prevent their withdrawal, they are preferably passed entirely through the sill and clinched or headed.

Connected to one of the post-sections 2 is a 60 wire, 12, which is thence carried diagonally downward over the faces of the fence-rails, to each one of which it is connected by an eye or staple, 13, its end being attached to a staple or spike, 14, driven through the lower rail into 65 the sill, as shown in Fig. 1.

This method of trussing the fence gives a structure having great strength and durability and enables the wires to be tightened at any time by driving the wedges farther or 70 by inserting larger wedges.

When the fence is complete, rail-riders 4^a are laid at the top, their ends resting between the ends of the post-sections 2 and lying upon the crossed ends of the trussing-wires 6 75 and 9. The weight of these rail-riders 4^a constantly applies a strain upon these wires, and as the fence is used they naturally tend to retain it in a strong, stiff, and properly-braced condition. By the riders being loose to gravitate downward and resting upon the upper sides of the crossed parts of the independent wires 6 and 9, the lower sides of the crossed parts of the wires are constantly pressed upon the uppermost rail, and as the ends of the 80 rails rest directly one upon the other the fence 85 is self-tightening, so that the weight of the riders by the crossed wires hold the rails in contact with each other, and the strain on the independent wires 6 and 9 constantly tends to draw the two sections of a post together.

To each of the posts is attached a wire girdle, 15, placed between two of the lower rails and encircling the two sections forming the post, whereby the same are held firmly together to give a stiff longitudinal connection to the several sections of fence and prevent the separation of the post-sections when lateral strain is imposed upon the rails. The crossing of the truss-wires 6 and 9 at the top 100 accomplishes the same function above as the wire girdles 15 do below, so far as the means for drawing the post-sections 2 together are concerned.

What I claim is— In a fence, the combination, with a post composed of two parallel sections between which the ends of the rails are inclosed, of 5 independent wires attached to said sections above the rails and crossed over the upper rail, a sill supporting the post and having two connections on each side of the fence, the wire being passed through one of the connections and fastened to the other, and a wedge

inserted between each pair of said connections and between the wire and the sill, substantially as shown and described.

In testimony whereof I have affixed my signature in presence of two witnesses.

EDWARD A. WELDS.
